UNITED STATES PATENT OFFICE.

ARMAND LEON FREDERIC LEFEVRE, OF ST.-DENIS, FRANCE, ASSIGNOR TO SOCIETE ANONYME DES ANCIENS ETABLISSEMENTS ROTCHKISS & CIE., OF ST.-DENIS, SEINE, FRANCE.

CHAIN GRATE FOR FURNACES USING MECHANICAL STOKERS.

1,261,564.

Specification of Letters Patent.

Patented Apr. 2, 1918.

Application filed July 8, 1915. Serial No. 33,707.

To all whom it may concern:

Be it known that I, ARMAND LEON FREDERIC LEFEVRE, a citizen of the Republic of France, residing at 5 Rue du Jambon, St.-Denis, Seine, France, have invented new and useful Improvements in Chain Grates for Furnaces Using Mechanical Stokers, of which the following is a specification.

The present invention relates to that kind 10 of furnaces using mechanical-stokers in which a chain-grate introduces the fuel into the furnace as the fuel is burnt.

The features of the invention will be explained in detail in the following description 15 considered in connection with the accompanying drawings, wherein:—

Figure 1 is a diagram of a chain grate furnace, embodying, for example, the features of the Klepke furnace described in 20 U. S. Patent No. 996,095.

Fig. 2 is a detail view on a larger scale showing, partly in side elevation and partly in section, a portion of a chain grate in which the features of the present invention 25 are incorporated.

Fig. 3 is a detail end view of an alternative construction of grate bar support.

In order that the invention may be thoroughly understood, let us explain the manner in which this kind of furnace, of which Fig. 1 is a diagrammatic view, is arranged. Broadly speaking, the arrangement consists essentially of an endless grate *a* on to which the fuel is fed by a distributor *b*; the coal 35 burns little by little and the residues resulting from the combustion are detached from the grate by a scraper *c*, above which they pass and whence they fall into the pit for the clinker. The principal rôle played by 40 the scraper is, however, to stop the passage of the air which otherwise would pass directly to the chimney without passing through the layer of fuel. When the chain passes around the driving wheel *d*, the 45 grate-bar supports leave between them much larger openings than those which separate them when they are on the two horizontal portions of the chain. The air would therefore tend to pass through these openings 50 instead of passing through the fuel. The scraper serves at the same time to separate the grate-chamber from the chimney.

Now, it would be preferable to do away with the scraper, which it is true, does de-

tach the clinker from the grate and passes it 55 on to the ash-pit, but is liable to the drawback that it gives rise to an accumulation of clinker which gradually forms a crust, the surface of which constantly increases and to the same extent diminishes the active 60 surface of the grate.

The object aimed at by the present invention is to dispense with the scraper and consequently to obviate the above drawback.

In order to obtain this result, the invention 65 consists in means which prevent the formation of large openings between the grate-bar supports *e* when they pass around the driving wheel *d*.

As in the known constructions, the grate-bar supports *e* are mounted on chains *a* and support the usual bars *f*, but they also comprise rigid transverse extensions *g*, *g*¹, which, in a straight length of the chains project inward beyond the horizontal plane wherein 75 lie the pivots of the chain links and are arranged in such a manner that the extension *g* of one of the supports is adjacent to the extension *g*¹ of the next support. The extensions *g*, *g*¹ have their adjoining faces 80 specially formed to coact, mutually and automatically, in all relative positions of the supports *e*, in establishing a joint between the adjoining supports which is substantially closed against the passage of air. 85 Consequently, and as shown in the drawings, whatever the angular position of the supports *e* as they rotate around the driving wheel, the openings between them remain practically invariable. The prolongations 90 *g*, *g*¹ can be attached to the supports or can be cast in one piece with them. In the same way instead of being symmetrical, as shown in Fig. 2, they may be unsymmetrical as shown by way of example in Fig. 3, the 95 effect remaining the same.

In order to prevent the direct passage of the air situate beneath the grate into the chimney, a screen of a special type is provided and is shown by way of example in 100 Fig. 2. This screen, which is located beneath the lower run or half of the grate consists essentially of a transverse wall *h* of refractory material, carrying a transverse flexible sheet *i*, which forms a joint against 105 the first transverse supporting roller *j* of the lower half of the chain. The wall *h*, which serves to protect the sheet *i* and the

roller j from the effects of the high temperature of the clinker thrown down by the bars f , can be inclined as shown in the drawing.

It is obvious that the joint assured by the extension g , g^1 at the rear end of the grate 5 as shown in Fig. 2 is likewise secured at the front end.

I claim:

1. In a chain grate for mechanical stokers, the combination with a chain, of grate bar supports fixed to said chain, said supports having rigid transverse extensions, which in straight lengths of the chain project inward beyond the horizontal planes 15 wherein lie the pivots of the chain links, the adjacent extensions of adjacent supports being formed to co-act, mutually and automatically, in all positions of said supports in establishing a joint between them which is substantially closed against the passage of air.

2. In a chain-grate for mechanical stokers, the combination, with a chain, of a roller supporting said chain, a wall of refractory material and a flexible sheet attached to said 25 wall and making a joint with said roller, said roller, wall and sheet being located transversely of said chain beneath its lower run.

3. In a furnace using a mechanical stoker, 30 the combination with a chain grate of a transverse support for said grate adjoining its lower run, a transverse flexible sheet making a joint with said support and a transverse wall of refractory material so located under said grate as to protect said support and said sheet against heat, as and for the purpose set forth.

ARMAND LEON FREDERIC LEFEVRE.
